His Attorney.

UNITED STATES PATENT OFFICE.

ROBERT H. McLAIN, OF SCHENECTADY, NEW YORK, ASSIGNOR TO GENERAL ELECTRIC COMPANY, A CORPORATION OF NEW YORK.

CONTROLLER.

1,247,436.

Specification of Letters Patent.

Patented Nov. 20, 1917.

Application filed September 18, 1916. Serial No. 120,687.

To all whom it may concern:

Be it known that I, ROBERT H. McLAIN, a citizen of the United States, residing at Schenectady, in the county of Schenectady, 5 State of New York, have invented certain new and useful Improvements in Controllers, of which the following is a specification.

My invention relates to devices for controlling electric circuits, and has for its 10 object the provision of improved means whereby the master switch which is ordinarily provided for controlling these circuits may be made considerably smaller, 15 lighter and less expensive than those heretofore used.

My invention relates more specifically to devices having a plurality of contacts which successively control a circuit or circuits, 20 such for instance as a controller which is commonly used for controlling an electric motor. Such controllers, ordinarily called "drum" controllers employ a rotatable cylinder having a plurality of contact segments 25 which engage corresponding stationary contact fingers to which the circuits to be controlled are connected. In the operation of controllers of this character especially where the circuit to be broken is of a highly inductive character, dangerous arcing may occur at the circuit interrupting contacts. This is true for instance in the case of a master switch or controller which controls separate electro-magnetically actuated 35 switches. This arcing has necessitated the use of a comparatively large controller in which the spacing between the successive steps of the controller and the spacing between the various circuit interrupting contacts are sufficiently large to take care of the 40 danger of the arc at one of the circuit interrupting contacts being deflected over to the adjacent contacts and thus causing a short-circuit within the controller itself, and also to make sure that the controlled circuits 45 will be positively deenergized. Furthermore, because of the heating effect of the arcs, the contact segments and fingers had to be made comparatively large to provide 50 sufficient cooling surface. The friction caused by the controller fingers riding up and down over the edges of the contact segments produced a further heating effect which had to be provided for by constructing 55 these parts larger than would otherwise

have been necessary. Of course, controllers have been constructed with large spacing between the successive operative positions and between the circuit making contacts and have been provided with blow out coils, arc 60 deflecting plates of insulating material between the contact segments and the like in attempts to obviate the difficulties and dangers above pointed out but these have all involved complications which have been expensive to construct and maintain and have also added considerably to the weight and size of the controller.

One of the objects of my invention is to make possible the use of a small, light and 70 inexpensive controller in which the spacing between the successive positions of the controller and the spacing between the various contacts are materially less than has heretofore been considered necessary. I accomplish this object by quickly deenergizing the controlled circuits and practically eliminating the dangerous arcing at the circuit interrupting contacts and minimizing the friction and wear of the parts.

To accomplish this object I connect a circuit having capacity to each coil circuit so as to suppress by absorption the arc at the circuit interrupting contacts and promptly deenergize the controlled circuits. More 80 specifically I connect a circuit having capacity in series with each coil circuit and across the circuit interrupting gap as the controller is moved to successively deenergize the coil circuits. The circuit having capacity acts 85 to quickly check the flow of current in the corresponding coil circuit and simultaneously suppress by absorption any arc which may tend to be formed at the circuit interrupting gap. More specifically, my invention provides a plurality of condensers, one 90 for each coil circuit, arranged to check the flow of current in the coil circuits quickly, thus causing the controlled switches to open very quickly and suppress the arcs at the 95 circuit interrupting contacts. The condensers may be placed either in the controller itself or be separate therefrom as desired. In one form of my device I provide, in combination with the above mentioned features, a controller having segments of insulation concentric with and having the same radius as the circuit making segments so that the controller fingers slide 100 directly from the circuit making segments 105 110

to the insulation without sliding up or down over the edges of the segments, thus minimizing the wear on the segments and fingers and at the same time avoiding the dangerous arcing by reason of the action of the circuits having capacity.

Referring to the drawings which show one embodiment of my invention, Figure 1 shows a system of control for an electric motor and Fig. 2 is a simplified end view of a part of a controller cylinder having a segment of insulation flush with the circuit making contact segment and showing the co-operating contact finger which is adapted to ride over these segments. Referring to Fig. 1, the motor 1 is connected to the supply circuit 2 by means of a trolley pole 3 and is connected to ground by means of the electromagnetically actuated switch member 4. The electromagnetically actuated switch member 5 is adapted to short circuit the armature controlling resistance 6, and the electromagnetically actuated switch member 7 is adapted to short circuit the armature controlling resistances 6 and 8. The highly inductive actuating coils of these switches are controlled by means of a master switch or controller 9 having two sets of relatively movable co-operating contacts. The size of these contacts, their spacing from one another and the spacing between the successive operative positions of the controller are all comparatively quite small. Associated with the controller are a plurality of circuits having capacity, the circuits having therein the condensers 10, 11 and 12. One side of each condenser is connected to its corresponding coil circuit and the other side is connected to the contact segments of controller 9. These condensers are adapted to check very quickly the flow of current in the switch coils and suppress any arcs which may tend to be formed at the master controller segments as the master controller is moved to deenergize the electromagnets. Referring to Fig. 2 the circuit making segment 13 and the segment of insulation 14 are secured to the shaft 15 of the master controller 9. The segment of insulating material 14 is flush with, closely adjoins, and has the same radius as the circuit making segment 13, so that when the controller is rotated so as to break the circuit between the stationary contact finger 16 and the circuit making contact 13, the finger 16 will ride directly from the contact segment onto the segment of insulation 14, and when the controller is rotated so as to make the circuit, the finger rides directly from the segment of insulation 14 to the contact segment, thus reducing to a minimum the wear on the edge of the circuit making segment 13 and the contact finger 16.

The operation of my device is as follows: In order to complete the circuit of the

motor 1 through the resistance 6 and 8 to ground, the master controller 9 is moved through the position *a* to the position *b*, when the coil 17 is energized causing the switch member 4 to close and complete the motor circuit. The circuit for the coil 17 is from the supply circuit 2, conductor 18, segment 19, through the coil to ground. Moving the controller to the position *c* energizes the coil 20, and by moving the controller to the position *d* the coil 21 is energized, causing the switch members 5 and 7, respectively to close and short circuit the resistance 6 and 8 in the motor circuit. The contact fingers ride directly from the sections of insulation to the contact segments with a very small amount of friction and wear.

To lower the speed of the motor, the controller is first moved backward to the position *c* when the controller finger rides off of the segment 13 onto the segment 14 of insulation with a small amount of friction. When this happens the condenser 10 is included in the circuit of coil 21 and across the interrupting gap between the contact making segment 13 and the controller finger 16. The condenser 10 quickly checks the current in the coil circuit causing the switch member 7 to be quickly opened removing the short circuit from the section of resistance 8. The condenser 10 connected across the insulation separating the contact segment 13 and the contact finger 16 suppresses any arc which may tend to be formed across this interrupting gap. When the controller is moved to the position *b* the condenser 11 is included in the circuit of coil 20 and across the interrupting gap between the contact segment and finger, and when the controller is moved to the position *a* the condenser 12 is connected in series with the coil 17 and across the corresponding interrupting gap, the action of the condensers 11 and 12 with respect to the coils 20 and 17 being the same as that of condenser 10.

By reason of the insulating material flush with and closely adjoining the movable segment and the action of these condensers in promptly suppressing the arcs at the circuit interrupting contacts and eliminating the danger of an arc flashing over from any one of the contact segments to the adjacent segments, it has been possible to use a master switch in which the spacing between the successive operative positions *a*, *b*, *c*, *d*, and the spacing between the segments themselves and the sizes of all the parts of the controller are comparatively quite small in proportion to the circuits controlled. This master switch or controller, may therefore be made considerably smaller, lighter, and less expensive to manufacture and maintain and its life in service considerably lengthened.

In accordance with the provisions of the patent statutes, I have described the principle of operation of my invention, together with the apparatus which I now consider 5 to represent the best embodiment thereof; but I desire to have it understood that the apparatus shown is only illustrative, and that the invention can be carried out by other means.

10 What I claim as new and desire to secure by Letters Patent of the United States, is:—

1. Controlling means for electric circuits comprising a master switch having a plurality of circuit interrupting contacts closely 15 spaced and having a plurality of operative positions in close proximity to one another, and means for increasing the safe capacity of the switch comprising a circuit having capacity connected to each of said circuits 20 and across the corresponding interrupting gap at the master switch.

2. Controlling means for electric circuits comprising a master switch having a plurality of closely spaced relatively movable 25 coöperating circuit interrupting contacts and having a plurality of operative positions in close proximity to one another, and means for increasing the safe capacity of the switch and for quickly deënergizing the controlled 30 circuits, comprising a plurality of condensers connected to the master switch across the interrupting gaps.

3. Controlling means for an electric motor comprising a plurality of electromagnetically actuated switches, a controller therefor 35 having a plurality of closely spaced relatively movable coöperating contacts and having a plurality of operative positions in

close proximity to one another, and means for increasing the safe capacity of the controller comprising a condenser connected to the coil circuit of each of said switches and to the controller across the interrupting gap at the controller. 40

4. Controlling means for electric circuits 45 comprising a plurality of stationary contacts, movable coöperating circuit interrupting contacts, insulating material flush with and closely adjoining the said movable contacts, and a condenser connected to each stationary contact and to the movable contacts so as to be included in the respective controlled circuit and across the insulating material between the stationary and movable contacts when these contacts are separated. 50 55

5. Controlling means for an electric motor comprising a plurality of electromagnetically actuated switches, a master switch for controlling the same having a plurality of stationary contacts to which the coil circuits of said electromagnetically actuated switches are connected and a plurality of movable coöperating contacts for making and breaking the coil circuits of said switches, insulating material flush with and closely 60 adjoining the said movable contacts, and a plurality of condensers each of which is connected to a stationary contact and to the movable contacts so as to be included in the respective coil circuit and across the 65 insulation between the stationary and movable contacts when these contacts are separated. 70

In witness whereof, I have hereunto set my hand this 16th day of September, 1916. 75

ROBERT H. McLAIN.
